CLAIM

The ornamental design of a wireless sensor, as shown and described.

DESCRIPTION

1. Wireless sensor

Fig. 1.1 is a front view of a wireless sensor showing the new design.

Fig. 1.2 is a back view of the wireless sensor.

Fig. 1.3 is a left-side elevation view.

Fig. 1.4 is a right-side elevation view.

Fig. 1.5 is a top plan view.

Fig. 1.6 is a bottom plan view.

Fig. 1.7 is an isometric view.

The broken lines represent portions of the wireless sensor that form no part of the claimed design.
